BULL FIGHTER TOY

Raymond H. Maxwell, 7 Wallace St., New Britain, Conn.

Filed May 1, 1961, Ser. No. 64,958

Term of patent 14 years

(Cl. D34—15)

FIG. 1 is a perspective view of the improved bull fighter toy, showing my new design.

FIG. 2 is a front view of the same.

FIG. 3 is a top plan view of the same.

The side opposite from FIG. 1 is substantially the same as shown in the drawing except that there is no ring on said opposite side.

I claim:

The ornamental design for a bull fighter toy, as shown and described.
